UNITED STATES PATENT OFFICE.

JASON E. HARRIS, OF HOWARD, KANSAS.

VARIABLE COMPRESSION AND SPEED DEVICE.

Application filed August 3, 1925. Serial No. 47,753.

- This invention relates to internal combustion engines and air compressors, and the primary object is to provide means for varying the stroke of the piston to effect a change 5 in piston displacement, whereby high compression shall be secured with a long stroke and low compression with a short stroke, the piston displacement therefore being in proportion to the length of stroke.
- Another object of the invention is to produce a construction which is susceptible of operation under high, low or intermediate compression and speed, a further object being to provide means for varying the compression 10 and speed without interrupting the operation of the device. Another object is to provide rotary exhaust-port valves for the cylinders and means whereby adjustment effecting a variation in the pressure and speed shall effect 15 conforming adjustment of the exhaust-port valves.
- With these and other objects in view, as will hereinafter appear, the invention consists in certain novel and useful features of construction and combinations of parts as hereinafter described and claimed, and in order that it may be fully understood, reference is to be had to the accompanying drawings, in which:—
- Figure 1 is a side elevation of an internal combustion engine embodying the invention.
- Figure 2 is a vertical longitudinal section of the same, with the pistons in elevation.
- Figure 3 is a vertical section on the line 35 III—III of Figure 1.
- Figure 4 is a section on the line IV—IV of Figure 3.
- Figure 5 is a view partly in central vertical and partly in elevation of Figure 4.
- Figure 6 is a vertical section corresponding to Figure 4 but with the crank in depending position as contrasted with Figure 4 in which the crank is in upstanding position, certain features shown in the latter figure being omitted in Figure 6.
- Figure 7 is a vertical transverse section of the bearings for the crank shaft which is shown in elevation, the figure also showing in section a worm wheel through operation of 50 which the crank shaft is adjusted for effecting variation in the compression and speed developed by the engine.
- In the said drawings, 1 indicates the stationary base or framework of the engine, 2 the 55 crank shaft mounted thereon, and 3 the crank of the shaft. The crank case 4 is mounted with a ball bearing relation around the bearings of the crank shaft, the case being made in sections for convenience in assembling. The cylinders 5 are bolted at their inner ends 60 and stand in radial relation to the crank case, and in the construction shown are adapted with the crank case, to revolve around the crank shaft which is stationary when the engine is working, although it is susceptible of 65 rotary adjustment at such time to permit of changing the engine from a high speed high compression to a low speed low compression engine, as hereinafter explained. The pistons 6 are adapted for reciprocation in the 70 cylinders, and are provided with intake-valves, not shown, as forming no part of this invention, for admitting combustible mixture from the crank case to the head or combustion chamber ends of the cylinders. The intake-valves mentioned form the subject matter of 75 Patent No. 1,627,032, May 3, 1927.
- The piston rods 7 are pivotally connected at their outer ends in the conventional or any preferred manner, not shown, with the 80 pistons, and at their inner ends are pivotally connected with the crank by means of collars 8. The detailed construction of the connection of the rods 7 with the crank forms the subject matter of Patent No. 1,627,031, May 85 3, 1927, and hence is not described or shown in detail herein.
- The bearings for the crank shaft have eccentric enlargements or hubs 9 constituting an outer part or member of the crank shaft 90 of the engine as the crank case is journaled for rotation thereon. It will thus be apparent that the axis of rotation of the cylinders is eccentric with respect to the axis of adjustment or rotation of the inner member of the 95 crank shaft, the latter as hereinbefore mentioned, being rotatably adjusted only when it is desired to vary the travel of the pistons and hence the compression and speed of operation. For high speed the crank will stand in a vertical or upright position as shown in Figures 2, 3, 4, 5 and 7. By such adjustment the pistons will have their longest travel and hence provide the greatest compression. For the shortest travel of the pistons and hence 100 lowest speed and compression, the crank occupies the pendent position shown by Figure 6. Positions of the crank intermediate the two extremes mentioned, will give corresponding piston strokes, compression and 105 speed. It will be obvious of course that the construction described with regard to the 110

crank shaft and cylinders may be reversed, that is to say, if the crank shaft is the driven element the cylinders will be stationary, but like the crank shaft in the present showing, will be capable of rotary adjustment so as to vary the length of stroke of the pistons with the corresponding changes in speed and compression hereinbefore mentioned.

In the construction shown, a worm wheel 10 is keyed on one end of the crank shaft and is engaged by worm 11 operable by a crank 12 as shown, or through any other means of transmitting power. For example, if the engine is used on a motor car, any suitable gearing or leverage arrangement may be provided which enables the driver of the car to effect adjustment of the shaft without leaving his seat. One of the hubs in which the crank shaft is mounted is provided with a passage 13 for conducting a combustible mixture into the crank case, whence it passes, as hereinbefore explained, to the combustion chambers of the cylinders at proper times for ignition by spark plugs 14.

Each cylinder is provided in the construction shown, with an exhaust port 15 communicating with a pocket 16, wherein is mounted a rotatable exhaust valve 17 through which the dead gases will be exhausted to the atmosphere through an exhaust manifold, not shown, of any conventional or preferred type. The pockets 16 and valves 17 stand at angles to the respective cylinders, and the stems 18 of such valves stand at corresponding angles 35 and are journaled near their inner ends in bearings 19 formed in the crank case, and within the latter the said stems 18 are equipped with worm gears 20 engaging a worm collar 21 secured on one of the eccentric hubs upon which the rotary part of the engine is mounted, the arrangement being such that revolution of the cylinders around the eccentric hubs and corresponding revolution of worm gears 20 around the eccentric worm 40 collar, will impart turning movement to the worm gears and hence corresponding rotary movement to the exhaust valves so that the ports thereof will register with the combustion chambers of the respective cylinders once in every other revolution of the latter around the shaft. It will be noted, by reference to Figures 4 to 6 inclusive, that the worm collar 21 is provided with arms 22 bearing against opposite sides of the crank of the shaft, so that when the latter is rotatably adjusted for the purpose mentioned, the worm collar is clearly turned so as to maintain the same relative position of the crank shaft and the exhaust ports at all times.

The operation of the engine which is of the four-cycle type is the same as any conventional four-cycle engine except that through a relative change in position between the cylinders and the crank shaft the length of stroke of the piston is varied so that the same

engine may be operated at varying speeds and hence with power dependent upon the character of work to be performed, it being also clearly apparent when operating under low compression and low speed, the volume of combustible mixture required is much less than when operating under high compression and high speed. With the eccentric mounting of the cylinders as shown, and the crank standing upright it will be apparent that the 75 pistons reciprocate their full distance, that is a distance almost double the length of the crank itself. With the crank shaft in vertically pendent position, the eccentric relation between the crank and the eccentric 80 9 is materially reduced with a corresponding diminution in the length of the pistons strokes and in the degree of compression of the combustible mixture in the combustion chambers of the pistons.

From the above description, it will be apparent that I have produced an internal combustion engine possessing the features of advantage set forth as desirable in the statement of the objects of the invention, and which is susceptible of modification in various particulars without departing from the principle of construction and mode of operation involved.

I claim:

1. In a variable compression and speed device, a crank shaft, a crank case disposed eccentrically of the axis of the shaft and around the crank of the latter, cylinders carried by the crank case, pistons in the cylinders, connecting rods between the pistons and the crank of the shaft, and means for varying the degree of eccentricity between the axis of the crank case and said crank by relative rotary adjustment between the shaft and crank case. 95

2. In a variable compression and speed device, a crank shaft, a crank case disposed eccentrically of the axis of the shaft and around the crank of the latter, cylinders carried by the crank case, pistons in the cylinders, connecting rods between the pistons and the crank of the shaft, means for varying the degree of eccentricity between the axis of the crank case and said crank by relative rotary adjustment between the shaft and crank case, 100 110 exhaust valves for the cylinders, and means actuated by change in eccentricity between the crank and the axis of the crank case, for effecting conforming adjustment of the exhaust valves.

3. In a variable compression and speed device, a crank shaft, a crank case disposed eccentrically of the axis of the shaft and around the crank of the latter, cylinders carried by the crank case, pistons in the cylinders, connecting rods between the pistons and the crank of the shaft, means for varying the degree of eccentricity between the axis of the crank case and said crank by relative rotary adjustment between the shaft and crank case, 115 120 125 130

rotary exhaust valves for the cylinders, a worm collar coaxial with the crank case and in fixed relation to the crank, and worm gears engaging the worm collar for rotation by and 5 relatively around it and connected to rotate the respective exhaust valves.

4. In a variable compression and speed device, a supporting frame, a shaft journaled therein and provided with a crank, a crank- 10 case journaled on the frame eccentrically of the axis of said shaft and inclosing said

crank, cylinders secured to and radially of the crank-case, pistons reciprocally arranged in the cylinder and pivotally linked to the crank, and means for rotatably adjusting the 15 crank to increase or decrease the distance between the centers of the crank-case and crank and thereby vary the length of stroke of the pistons.

In witness whereof I hereunto affix my sig- 20 nature.

JASON E. HARRIS.
